THUMB GUARD

William R. Rasmussen and Thomas Ogden,
Lynwood, Calif.

Application June 5, 1931, Serial No. 542,380

1 Claim. (Cl. 2—21)

This invention relates to improvements in a thumb guard, its primary object being to provide a guard for the thumb to be used when peeling potatoes or fruit or when cutting or 5 carving wood and numerous other articles.

A further object is to provide such a thumb guard that will be very inexpensive to manufacture and an improvement in the art.

With these and other objects in view that may 10 appear while the description proceeds the invention consists in the novel construction and arrangement of parts as hereinafter more specifically set forth, claimed, and shown in the accompanying drawing forming a part of this 15 present application and in which.

Fig. 1 is a perspective view of the improved thumb guard.

Fig. 2 is a cross-sectional elevation of the same.

Fig. 3 is a view showing the guard on the 20 wearer's thumb.

Referring more in detail to the drawing in which similar reference characters designate corresponding parts throughout the several views it will be seen that the invention comprises a tubular 25 shaped thumb guard 10 having a closed concave top 11 and a corrugated front portion 12. The lower edge 13 of the guard is rolled and provided with a recess to fit the crotch between the thumb and index finger of the hand whereby the guard 30 is held against rotary movement.

The thumb guard will be made of some suitable metal such as aluminum. It will be worn

on the thumb in such a manner as to catch the knife when pressed toward the thumb, the corrugations 12 will prevent the knife from slipping when it touches the guard. The concave top 11 is for the same purpose.

It is believed that the construction and advantages of the structure shown may be apparent from the foregoing paragraphs taken in connection with the accompanying drawing without further detailed description.

While the preferred embodiment of the invention has been disclosed it is understood that minor changes in the details of construction, may be resorted to within the scope of what is claimed, without departing from the spirit of the invention.

We claim:—

A thumb-guard comprising an elongated tubular metal body conforming in shape to the contour of the thumb, said body having its upper 75 end closed and concaved, the lower end of the body being disposed on a plane at right angles to the axis of the body and provided with a recess in its peripheral edge to fit the crotch of the thumb whereby the guard is held against rotary 80 movement, and corrugations formed in one side of said body for a portion of its length, said corrugations being disposed at right angles to the longitudinal axis of said body.
